UNITED STATES PATENT OFFICE.

JOHN F. FORWARD, OF SAN DIEGO, CALIFORNIA.

QUARTZ-MILL.

SPECIFICATION forming part of Letters Patent No. 735,234, dated August 4, 1903.

Application filed January 18, 1902. Serial No. 90,337. (No model.)

To all whom it may concern:

Be it known that I, JOHN F. FORWARD, a citizen of the United States, residing at San Diego, in the county of San Diego and State 5 of California, have invented a new and useful Quartz-Mill, of which the following is a specification.

My invention is an improved quartz-mill; and it consists in the peculiar construction 10 and combination of devices hereinafter fully set forth and claimed.

In the accompanying drawings, Figure 1 is a vertical sectional view of a quartz-mill embodying my improvements. Fig. 2 is a detail 15 top plan view, partly in section, of the adjustable frame and the bearing which is detachably connected thereto. Fig. 3 is a top plan view of my improved quartz-mill. Fig. 4 is a detail top plan view of the base. Fig. 5 is a detail top plan view of the fixed conical 20 grinding element, showing the channels therein. Fig. 6 is a plan view of the upper adjustable frame with a part broken away to show the groove therein. Fig. 7 is a detail 25 plan view of the detachable bearing used in connection with said top frame. Fig. 8 is a plan view showing the top frame with the bearing supported thereon, but prior to being turned to its operative position. Fig. 9 is a 30 plan view showing the top frame with the bearing mounted therein ready for operation. Figs. 6, 7, 8, and 9 are on a somewhat larger scale than the remaining figures of the drawings.

In the embodiment of my invention here shown the base 1 is a casting comprising a central portion 2, radial-arms 3, which extend outwardly therefrom and are formed with downwardly-extending feet 4 at their outer 35 ends, and side bars 5, which connect the radial arms together and brace and strengthen the same. In the upper side of the hub portion 2, at the center thereof, is formed a recess 6, the sides of which are non-circular, usually 40 angular, as shown in the drawings, and in the center of the said central or hub portion is a vertical opening 7, the upper end of which communicates with said recess. Vertical supporting - columns 8 have their lower ends 45 screwed to the outer portions of the arms 3, and are thereby detachably secured to the base.

A fixed grinding element 9 of conical form, having a grinding-surface 10 extending outwardly from the base thereof, is a hollow casting 55 adapted to fit on the central portion 2 of the base and formed with a non-circular locking projection 11 on its lower side, which fits in the non-circular recess 6 of the base and is secured thereto by a bolt 12. The said bolt 60 passes through an opening in the locking projection and through the opening 7 in the center of the base. Thereby the fixed conical grinding element may be securely attached 65 to the base, so that it cannot revolve thereon, and yet is adapted to be readily removed from the base when the mill is disassembled for transportation or for other reasons. The conical portion of the fixed grinding element is provided with channels 13, which extend 70 from the grinding - surface 10 thereof upwardly to near the apex of the cone, and the said channels are deepened and widened downwardly, as shown.

A revoluble grinding element 14 (here 75 shown as of cylindrical form and with a cylindrical bore 15) is disposed on and around the fixed grinding element and is provided at its base with a detachable grinding portion 16, which bears upon the grinding-surface 10 80 of the fixed grinding element 9. The detachable portion 16 is secured to the main portion of the revoluble grinding element by ears or lugs 17 and bolts 18, as shown in Fig. 1. It will be observed by reference to the said Fig. 85 1 that the bore 15 forms a downwardly-contracting grinding-space around the conical portion of the fixed grinding element 9. The revoluble grinding element 14 is provided at its upper end with an upwardly-extending 90 tubular feed-shaft 19, which communicates with the bore 15.

A vertically - adjustable frame 20 (here 95 shown as a segmental casting) is provided with radial arms 21, having openings at their outer ends to receive the supporting-columns 8. The upper portions of the latter are screw-threaded and provided with adjusting-nuts 22, which bear, respectively, below and above the arms of the frame 20, and hence 100 the latter is vertically adjustable on the supporting standards or columns 8, as will be understood. Two of the arms 21 of frame 20 are connected together by a bar 23, which is

here shown as an integral portion of the frame or casting 20 and is formed at its center with a bearing 24 for a power-shaft 25, which is provided at its inner end with a detachable 5 pinion 26 and is shown as having a crank-wheel 27 at its outer end. It will thus be seen that the power-shaft may at any time be slid out of its bearing, and thus removed, by simply previously detaching the pinion 26, 10 which latter may be held upon the shaft by means of a set-screw extending through the collar thereof or in any other suitable manner. The frame or casting 20 is formed with a central segmental opening 28, communicating 15 with the space 28', inclosed between the cross-bar 23 and the arms 21, connected by said cross-bar, and it has an annular groove 29 in its inner side or face, from the upper side of which extend slots 30, communicating 20 with the upper side of the casting and of which there are a suitable number disposed at appropriate distances apart. A bearing 31 (here shown as forming nearly a complete circle and which is preferably cast) is adapted 25 to be fitted in the segmental opening 28 of the vertically-adjustable frame 20 and is formed with peripheral lugs 32, which when they are disposed coincident with the slots 30 enable the said bearing to be placed in or removed 30 from the opening in the vertically-adjustable frame 20, and the said bearing is secured to the said vertically-adjustable frame 20 by partly turning the same after its lugs have entered the groove 29 through the 35 slots 30, so that the said lugs bear under the flange formed above said groove 29. A lock-pin 33 is then fitted in registering openings in one of said lugs and in the frame 20 to lock the bearing 31 in said frame. The said 40 bearing 31, which is thus detachably secured to the vertically-adjustable frame 20, bears on the upper end of the revoluble grinding element 14, and the tubular feed-shaft 19 of the latter is journaled in the said bearing and 45 extends upwardly therefrom. By adjusting the frame 20 on the columns or standards 8 the lower grinding portion of the revoluble element 14 may be caused to bear with any desirable degree of compression upon the 50 grinding-surface 10 at the base of the conical fixed grinding element 9. The opening 28 of the vertically-adjustable frame 20 is of greater diameter than the revoluble grinding element, so that the latter, when the bearing 31 has 55 been turned to disengaging position, may be lifted, together with the bearing 31, and the revoluble fixed grinding element may be thus lifted through the opening 28 of the frame 20 when it is desired to remove the revoluble 60 grinding element from the mill. It will be understood that by this construction of the vertically-adjustable frame and the bearing, which is detachable therefrom, the revoluble grinding element may be removed from 65 the mill without the necessity of removing or altering the adjustment of the frame 20. It will also be seen that the fineness of the

grinding may be regulated by properly adjusting the frame carrying the bearing 31 with relation to the upper grinding element, 70 since the latter may under no circumstances rise beyond the point to which the frame carrying said bearing is adjusted.

On the upper portion of the tubular feed-shaft 19 of the revoluble grinding element is 75 keyed or otherwise secured a beveled gear-wheel 34, which engages the beveled pinion 26, and being disposed above the detachable bearing 31 the latter, which bears on the upper end of the revoluble grinding element, is 80 connected revolubly thereto.

When it is desired to dismember the machine, this may be accomplished by removing the pin 33 and slightly turning the detachable bearing-plate 31 until the lugs 32 of the latter are in alinement with the slots 30. The pinion 16 is also loosened upon the power-shaft, thus permitting the latter and the said pinion to be removed. The bearing-plate 31, with the cylinder 14 and the bevel-gear keyed upon the 90 feed-shaft of said cylinder, may then be lifted out and removed without disturbing the upper frame 20 of the device.

In a machine of this character, which in order to be successfully operative must necessarily be of considerable weight, it is extremely desirable that the construction shall be such that not only said machine may be quickly and conveniently dismembered to enable it to be conveniently transported to the place where it is to be used, which invariably involves passage over rough and sometimes almost impassable roads, but it is also desirable that when thus dismembered the weight of the parts should be distributed as 95 evenly as possible. It has been found in practice that with the parts relatively proportioned according to the requirements of a working machine the weights of the parts concerned will be more nearly equalized by 100 assigning the recess to the base and the projection to the grinding member, the change in the relative weights of the elements concerned thus being double the weights actually transferred.

Having thus described my invention, I 105 claim—

1. In a quartz-mill, a base having a recess, in combination with a grinding member having a projection detachably engaging said recess.

2. The combination with a base having a non-circular recess, of a grinding member composed of a hollow cone having a frustum-shaped lower end and a non-circular lug extending inwardly from the lower edge thereof, said lug engaging the non-circular recess in the base and connected detachably therewith by means of a fastening member extending through alining perforations in said lug and 125 base.

3. In a quartz-mill, the combination of a fixed conical grinding element, a revoluble grinding element bearing thereon and having

a bore into which the fixed conical grinding element extends, and provided further with an upwardly-extending feed-shaft at its upper end, a vertically-adjustable frame, having an opening of greater diameter than the revoluble grinding element, and a bearing in which the feed-shaft of the revoluble grinding element is journaled, said bearing and vertically-adjustable frame having coacting devices, to secure the bearing detachably in said opening, substantially as described.

4. In a quartz-mill, the combination of a fixed conical grinding element, a revoluble grinding element bearing on and having a bore into which the fixed conical grinding element extends, and provided further with an upwardly-extending feed-shaft at its upper end, a vertically-adjustable frame having an opening of greater diameter than the revoluble grinding element, a power-shaft journaled in a bearing in said frame and having a beveled pinion, a bearing in which the feed-shaft of the revoluble grinding element is journaled, said bearing being detachably secured on the frame, and a beveled gear-wheel, secured on the feed-shaft above the detachable bearing, and when the latter is on the frame engaging the said beveled pinion, substantially as described.

5. In a device of the class described, the combination of a lower frame, lower and upper grinding members, a vertically-adjustable upper frame having an opening and outwardly-extending arms, a cross-bar connect-

ing two of said arms and having a bearing 35 thereon for a power-shaft, a bearing-plate engaging the opening of the upper frame, means for securing the said bearing-plate detachably in said opening to revolubly engage the feed-shaft of the upper grinding member and 40 to confine the latter against upward movement, a pinion upon the power-shaft and a gear-wheel upon the feed-shaft of the upper grinding member.

6. In a device of the class described, the 45 combination of a lower grinding member, an upper grinding member, a vertically-adjustable upper frame, and a bearing-plate connected detachably with the latter and confining the upward movement of the upper grinding member, substantially as set forth.

7. In a device of the class described, the 50 combination of the lower grinding member, an upper grinding member having a tubular feed-shaft, a vertically-adjustable upper frame member and a bearing-plate connected 55 rotatably and detachably with the latter, revolubly engaging the feed-shaft of the upper grinding member and confining the latter against upward movement.

In testimony that I claim the foregoing as my own I have hereto affixed my signature in the presence of two witnesses.
